PROCESS FOR CRACKING OILS

Will K. Hilmes, Port Arthur, Tex., assignor to The Texas Company, New York, N. Y., a corporation of Delaware

Application July 25, 1928, Serial No. 295,304

3 Claims. (Cl. 196—49)

This invention has reference to the production of gasoline or similar light hydrocarbons through the cracking or conversion of higher boiling oils into lower boiling oils by the application of heat and pressure. It relates particularly to the disposition of the heavy residual oils which result from ordinary processes for effecting conversion of the character mentioned.

An object of the invention is to provide for maximum efficiency in the utilization of the heat employed in the cracking process. In attaining this end, it is proposed to provide a closed cyclic system which, in the course of operation, will bring about the formation of only two final products in the nature of a light, marketable gasoline product and a heavy fuel oil. Incidental to the accomplishment of the foregoing result, it is contemplated to strip the residual material resulting from the conversion in such a way as to yield a maximum amount of the lighter oils, as well as stock which may be recycled for further cracking. By virtue of this phase of the process, there is brought about a greater total yield of the lighter constituents since there is not only effected a more complete separation of the desired lighter ends, but a greater percentage of the intermediate constituents which may be effectively subjected to further cracking are recycled while hot.

Briefly, the invention has in view the employment of a tar or residue distillation chamber directly in conjunction with a cracking system of any suitable form in such a way that the heat which would otherwise be wasted is put to full advantage. This includes not only the utilization of the heat content of the residues themselves, but also of the heat of the flue gases which are generated in the course of heating the stills embodied in the cracking units. Toward this end it is proposed to mount an expansion chamber directly in the furnace surrounding the stills, or otherwise directly in the path of the flue gases from this furnace and to discharge into such chamber the residues taken from the stills. Due to a considerable reduction in pressure on the oil, which is contemplated in its passage into the chamber, volatilization of a large percentage of the material will take place immediately and further volatile constituents will be driven off through the external application of the heat of the flue gases or other source. By the application of external heat to the residue or tar stripping chamber, a satisfactory separation between the volatile constituents and the heavier fuel oil or residual material is accomplished in the single

stage, thus eliminating the necessity for further distillation of the tar.

Another feature of the invention is in the provision of a plurality of separate heating units, such as coils, in a system of the above general character so that the several oil bodies requiring the application of heat may be subjected to the conditions most suited to their requirements. Thus, the lighter condensates which are knocked back in the fractionation of the vapors generated in the system may be subjected to somewhat different treatment from the fresh charge of oil being constantly introduced into the system. A further distinction as to operating conditions may be brought about between the two condensates evolved, i. e., that evolved from the fractionation of the vapors from the pressure cracking system and that evolved from the fractionation of the vapors released in the tar stripping chamber.

A still further feature of the invention has to do with a preferred and advantageous mode of operation of the system with particular reference to the amount of backtrap or condensate returned from the fractionator associated with the conversion unit to such unit. Heretofore, it has been the usual practice to return condensate of this character in an amount less than twice the amount of fresh charge introduced into the system and frequently little more than equal to the amount of fresh charge. It has been discovered, however, that the return of a relatively large amount of this condensate, say, for example, three or four or more times the amount of fresh charge, brings about very advantageous results, particularly in a system embodying the several features of the present invention. One obvious advantage is that the speed of flow of the liquid, combined charge and returned condensate through the heating unit, such as a coil, is increased to such an extent that the danger of depositing carbon and developing hot spots is largely eliminated. At the same time the burden placed upon the heating unit is not excessive due to the fact that the condensate returned to it is already very hot and needs to receive very little additional heat.

With the foregoing and other incidental objects and advantages in view, the invention will now be described in detail by reference to the accompanying drawing in which the single figure illustrates diagrammatically one suitable form of apparatus for carrying out the invention.

Referring now to the drawing, there may be provided a pump 8 connected to any suitable

source of supply of any suitable type of cracking stock, such as gas oil, for example, which it is desired to employ in this system. This material may be forced by the pump through a line 9, a heat exchange coil 10 and a line 11 into a coil 12 forming one section of a heating coil mounted in a furnace 14. If desired, the heat exchange coil 10 may be by-passed either in part or in whole. The coil 12 may either be a distinct unit, which may be termed an economizer by virtue of the fact that it is merely in the path of the flue gases which are more directly applied to the heating of a lower section 13 of the coil, or, if desired, the two sections may constitute merely separate portions of a single coil. From the outlet end of the economizer section 12, a line 15 is adapted to convey the charge to the upper end of a second heating coil 16 mounted in another furnace 17, which may receive heat from any suitable source.

A by-pass line 18 may be provided for the purpose of permitting all or a portion of the charge to flow directly from the line 11 to the coil 16, if desired, and for the purpose of regulating the flow through the lines 11, 15 and 18, a plurality of valves 19 may be suitably placed in the lines 11 and 18. It is contemplated as desirable to maintain a pressure of between 150 and 600 pounds, preferably about 400 pounds, on the oil as it leaves the heating coils, although pressures outside of this range may be employed, if desired.

Upon leaving the coil 16, the temperature of the oil should be between 700° and 950° F., preferably about 850° F., and it may then be passed by a transfer line 20 to one or more of a series of stills or drums 21.

While two separate heating coils have been disclosed herein and form a part of an ideal embodiment of the invention, this is not essential and one, for example coil 16, may be eliminated altogether, if desired. If this is done, the charge, after passing through the section 12, will be passed directly to the section 13 of the coil in the furnace 14 and will emerge under the same conditions of temperature and pressure as explained above. To bring about this elimination of coil 16, it will only be necessary to close a valve 22 in the line 15 and open a valve 23 in a by-pass connection 24 communicating between the section 12 and section 13 of the coil. In this event, the charge upon leaving the lower end of the coil 13, may be passed by a transfer line 25 to one or more of the series of stills 21.

It is not necessary that more than a single still or drum should be provided but it has been found preferable to employ a plurality of between two and four. Four have been illustrated in the accompanying drawing and these are interconnected by means of a plurality of lines 26 which provide communication between the liquid bodies, as well as the vapor spaces of the several stills. While the stills may, if desired, be merely heat-insulated, all are preferably mounted within a furnace 27, which is heated by any suitable means and which is adapted to supply heat to the oil in the stills through the mid-portion of the walls of the latter. The heat so applied will preferably be only sufficient to maintain the temperature of the oil above the cracking point by way of compensating for the heat of vaporization of the lighter constituents which pass off in vapor form.

A vapor line 28, connected to the vapor space of one or more of the stills, may serve to con-

duct the evolved vapors to a dephlegmator or fractionating tower 29, which may suitably be of bubble tower construction. Here a separation between the heavier portions, which will be condensed, and the light portions, which will remain in vapor form, will take place. The lighter vaporous constituents may be carried through a reflux condenser 30 housing the heat exchange coil 10 and through a line 31 to a suitable condenser 32, and into a storage or accumulator drum 33. Any suitable method may be adopted for providing a cooling medium, as by way of reflux, at the top of the tower 29; for example, a portion of the condensate collected in the drum 33 may be carried through a pipe 34 to a pump 35, which may then serve to return it to the top of the tower through a line 36.

From time to time during the operation of the system, or continuously, if desired, the heavy residual oil which tends to collect in the bottom portions of the stills 21 may be drawn off through tar-drawing lines 37 and discharged into a main 38, which will convey the residues to an expansion or pressure relief valve 39 and into an expansion chamber 40. Due to the heavy, tarry nature of the residue so withdrawn, it will be found preferable to effect the withdrawal intermittently so that a greater flow may be provided at periodic intervals to keep the connections 37 free from obstructing carbon deposits. Where a battery of stills, such as illustrated, is employed, it will ordinarily be preferable to withdraw the tar more frequently from the last of the series and to withdraw it after only increasingly greater intervals from the remaining stills. Suitable valves will be provided in the drawoff lines 37 for controlling the withdrawal of the residue. In the event that continuous tar drawing is desired, it will be found advantageous to provide a by-pass line 371 around the valve in the line 37 for, say, the last two stills. One or more of these by-pass lines may be kept continuously open to withdraw a portion of the residue as it accumulates. At the same time it will be found desirable to open up the lines 37 at periodic intervals to draw off greater quantities of the residue and keep these lines cleared.

Within the chamber 40 the pressure will preferably be maintained as near atmospheric as possible in order to produce a maximum flashing effect, but it will be obvious that this pressure will fluctuate to a certain extent due to the intermittent introduction of at least a part of the residue into it. The chamber 40 may be provided with a series of baffle plates 401 and suitable scrapers 402 and, as shown, is preferably mounted directly in the furnace 27, although it may be mounted in any other suitable way to receive the heat of the flue gases generated within the furnace 27 or to receive heat from other sources. It will be apparent that as a result of the reduction in pressure on the residue, and due to the additional heat applied to the chamber 40, a very large percentage of the oil will be flashed, or otherwise converted, into vapor, which may be carried through a vapor line 41 to any suitable form of dephlegmator or fractionating column 42. This may suitably be in the nature of a rock tower, or preferably a bubble tower. Those portions of the vapors which remain as such in their passage through the tower will be carried through a line 43 to a condenser 44 and may be discharged into an accumulator drum 45. A part of this condensate may be returned by means of a pump 46

and a line 41 to the top of the column 42 as a means of cooling the latter. The products collected in the drum 45 may, under certain conditions of operation, be in the nature of a marketable grade of gasoline, as when the necessary cooling regulation is provided for the tower 42. However, it will be found preferable to operate under conditions not calculated to produce a substantially finished gasoline at this point. Furthermore, it will be found that this product will at best have a greater tendency to go off color, due to polymerization of some of the constituents, than is the case with the products collected in the drum 33. For this reason it may be found preferable to pass the remainder of the condensate collected in the drum 45 directly into the first mentioned fractionating tower 29, where it will provide some of the necessary cooling and reduce the requirement of reflux from the drum 33. At the same time the condensate so subjected to further fractionation under pressure in the tower 29 will undergo an action of polymerization which will tend to render the product color-stable. It will, in fact, pass in large part with the lighter vapors from the line 28 into the drum 33 as a good quality naphtha. To dispose in this way of the part of the condensate not returned to the column 42, a pipe connection 470 may be provided from the pump 46, or a separate pump may be employed if desired. It will be clear that it will be necessary to boost the pressure of the condensate by means of the pump 46 from substantially atmospheric to that maintained within the tower 29 and for this reason a different pump may be found preferable. If this mode of operation is adopted, the tower 42 may, if desired, be so regulated that a heavier product will be carried over, as for example a fraction including some of the kerosene constituents, although, preferably, the endpoint will be kept within the gasoline range. The point of entry of the condensate into the tower 29 will, for best results, depend upon the nature of the material. If its endpoint is near that of the final product, it may be introduced through the line 470, while if its endpoint is higher, it may be introduced through the branch line 471.

From the base of the fractionating tower 29, the condensate which is knocked back and which may be termed "backtrap" is withdrawn by means of a pump 48 and may be passed through a line 49 to the heating coil in the furnace 14. Various optional methods of handling the backtrap through the heating coil are afforded by the present disclosure. The particular course through which it is desirable to force this condensate will depend largely upon the method of handling the fresh charge of oil which is selected out of the several ways hereinbefore indicated. If the fresh charge is to be passed directly to the coil 16 through the by-pass line 18, previously described, then the backtrap may advantageously be passed through a line 50 to the upper end of the coil 12. At the same time the valves 22 and 23 should be so adjusted that the re-heated backtrap will be passed through the coil 13 and be delivered into the transfer line 25 at a somewhat higher temperature than that of the fresh charge of oil leaving the coil 16. This is done for the reason that the backtraped material is somewhat more difficult to crack than the fresh charge and should preferably be raised to a higher temperature.

Now, if the system is to be so operated that the fresh charge is first passed through the economizer section 12 within the furnace 14, before

being passed to the coil 16, it will be advantageous to pass the backtrap directly to the inlet of the coil 13. To bring about this mode of operation, the line 50 may be provided with a valve 51 which, when closed, will tend to direct the condensate into a line 52 leading directly to the inlet of the coil 13. Since the condensate, before entering the coil, is already at a temperature which may well be in the neighborhood of 700° F., the temperature at the outlet of the coil 13 will still be quite high and probably in excess of that of the fresh charge leaving the coil 16.

Should the system be so operated as to entirely eliminate the coil 16, as has been explained, in which case the fresh charge will be passed through both of the coils 12 and 13, it will be desirable to introduce the backtrap at a lower point in the coil 13 where its temperature will correspond more nearly to that of the fresh charge. To enable the passage of the oil in this way, the line 52 may be provided with a valve 53 which, when closed, together with the valve 51, will direct the condensate into a line 54 leading to a suitable point near the bottom of the coil 13. A valve 55 should be provided in this line so as to close it off in the event that one of the first two mentioned modes of operation is adopted.

In a similar way the condensate which collects at the base of the tower 42 and which may be termed "cycle stock", is adapted to be withdrawn by means of a pump 56. Several optional courses may likewise be followed in the disposition of the cycle stock. It may, if desired, be passed through a line 57 to a point of juncture with the line 49 so as to merge the two condensates for passage in any one of the three ways indicated with respect to the backtrap. However, a different course may be found desirable, particularly where the fresh charge is being passed first through the coil 12 and then the coil 16. The cycle stock will be of a somewhat lower temperature than the backtrap whereas it will be of a considerably higher temperature than the fresh charge. Its temperature may correspond more nearly to that of the charge after having passed through the coil 12 and for this reason it may be advantageously merged with the charge before the latter enters the coil 16, or, if desired, at an intermediate point in this coil. To effect this disposition of the cycle stock, the line 57 may be provided with a valve 58 which, when closed, will direct the condensate into a line 59 joining the line 15 or entering the coil 16 at any suitable point. A valve 60 in the line 59 should be provided, so that when closed it will enable the passage of the oil in the first way indicated. Obviously, if desired, both of the valves 58 and 60 might be left partially open to any extent desired to split the cycle stock between the two courses available to it.

It has previously been suggested, as a feature of the invention, that the ratio of the backtrapped material to the fresh charge should preferably be quite large, for example in the neighborhood of three or four to one. Thus, where a charging rate of, say, 100 barrels per hour of fresh charge is maintained, the backtrap may to advantage be returned to the extent of 300 or 400 barrels per hour, or even more. It is to be understood, however, that this is optional and that a smaller amount of backtrap may be developed, if desired. At the same time the cycle stock, or condensate from the chamber 42, may well be developed in quantities of 100 to 300 barrels, or more, per hour, although operations tending to

produce somewhat less cycle stock than the quantity of charge used are deemed preferable. Where the backtrap and cycle stock assume the relatively high values mentioned, and the two heating coils are in operation, it will be found advantageous to pass the cycle stock through the line 59 directly to the coil 16, while the fresh charge is passed first through the coil 12 and then through the coil 16 and the backtrap is passed 10 only through the coil 13. Operation of the unit in this way will bring about relatively high speeds of flow of the material through the hotter portions of both the coils 13 and 16 so that the oil may be raised to a relatively high temperature 15 without danger of excess deposition of carbon or the burning out of the tubes of the coils.

From the base of the expansion chamber 40 a residue drawoff line 61 may be provided and may serve to pass the heavy unvaporized portions 20 of the tar to any suitable storage. This residue will be in the nature of a heavy fuel oil fraction, which is unsuitable for further cracking but is of good quality for fuel purposes. It will be recognized that in the preferred mode of operating the system, only two products will be formed, these being the gasoline fraction collected at 33 and the fuel oil discharged through the line 61. In addition, there will, of course, be formed a small amount of coke and a small 25 amount of fixed gases but these may be ignored.

While one suitable form of apparatus for carrying out the invention has been disclosed herein, and certain definite operating conditions have been suggested, it should be understood that these 30 are given merely for the purpose of illustration and that many variations may be made within the scope and spirit of the invention. It is desired to be limited in the application of the invention only by the scope of the claims which follow:

40 What I claim is:

1. In a process for the conversion of higher boiling hydrocarbon oils into lower boiling ones, the process that comprises passing fresh charging stock through a tubular heater and raising the oil to a cracking temperature therein, passing the oil thus heated into a cracking still wherein the oil is subjected to cracking and vaporization under superatmospheric pressure, subjecting evolved vapors to fractionation to condense and thereby separate heavier fractions therefrom, withdrawing residue from the cracking still and reducing the pressure thereon to effect vaporization, subjecting evolved vapors to

fractionation to form a condensate, passing a portion of said condensate through said tubular heater and directing the heavier fraction and another portion of the condensate through a separate tubular heater, and thereafter passing the condensates from said heater to said cracking still. 5

2. In a process for the conversion of higher boiling hydrocarbon oils into lower boiling ones, the process that comprises passing fresh charging stock through a tubular heater in a heating zone and then through another tubular heater in another heating zone whereby the oil is heated to a cracking temperature, passing heated oil into a cracking still wherein the oil is subjected to cracking and vaporization under superatmospheric pressure, subjecting evolved vapors to fractionation to condense and thereby separate heavier fractions therefrom, withdrawing residue from the cracking still and reducing the pressure thereon to effect vaporization, subjecting evolved vapors to fractionation to form a condensate, passing a portion of said condensate through the tubular heater in the second mentioned heating zone, directing said heavier fraction and another portion of said condensate through a separate tubular heater in the first mentioned heating zone and thereafter passing the condensates to said cracking still. 10 15

3. In a process for the conversion of higher boiling hydrocarbon oils into lower boiling ones, the process that comprises passing fresh charging stock through a tubular heater in a heating zone and then through another tubular heater in another heating zone whereby the oil is heated to a cracking temperature, passing the heated oil into a cracking still wherein the oil is subjected to cracking and vaporization under superatmospheric pressure, subjecting evolved vapors to fractionation to condense and thereby separate heavier fractions therefrom, conducting the heavier fraction through a separate tubular heater in said first mentioned heating zone, withdrawing residue from the cracking still and reducing the pressure thereon to effect vaporization, subjecting evolved vapors to fractionation to form a condensate, passing a portion of said condensate through said second mentioned heating zone, directing another portion of said condensate into the separate tubular heater in the first mentioned heating zone and thereafter passing the condensate to said cracking still. 20 25 30 35 40 45 50
